Des. 210,847

Patented Apr. 23, 1968

210,847

MEDICINAL DISPENSING DEVICE OR THE LIKE

Ray Aron, West Orange, N.J., assignor to Organon, Inc.,
West Orange, N.J., a corporation of New Jersey

Filed Feb. 27, 1967, Ser. No. 5,970

Claims priority, application Canada Oct. 14, 1966

Term of patent 14 years

(CL D52—2)

FIG. 3

FIG. 1

FIG. 1 is a top plan view of a medicinal dispensing device, or the like, embodying my new design;

FIG. 2 is a bottom plan view thereof; and

FIG. 3 is a side elevation thereof.

I claim:

The ornamental design for a medicinal dispensing device or the like, as shown and described.
